UNITED STATES PATENT OFFICE.

ANDERS JOHAN EMIL RYLANDER, OF STOCKHOLM, SWEDEN.

MEANS FOR CONTROLLING AND REVERSING VESSELS.

Application filed May 31, 1922, Serial No. 564,904. Renewed August 26, 1924.

To all whom it may concern:

Be it known that I, ANDERS JOHAN EMIL RYLANDER, a subject of the King of Sweden, residing at Katarina Kyrkobacke 2, Stockholm, in the Kingdom of Sweden, have invented certain new and useful Improvements in Means for Controlling and Reversing Vessels, of which the following is a specification.

10 The present invention has for its object to provide improved means for controlling and reversing vessels without reversing the motive power agent.

15 For a consideration of what I believe to be novel and my invention, attention is directed to the accompanying specification, and the claims appended thereto.

20 In the accompanying drawings which are illustrative of my invention, Fig. 1 shows a side elevation of a rudder in collapsed position; Fig. 2 is a top plan of the said rudder in the same position; Fig. 3 is a front elevation of the rudder in intermediate position; Fig. 3^a is a section of a joint in the rudder on an enlarged scale; Fig. 4 is a top view of the rudder in the said intermediate position; Fig. 5 is a front elevation of the rudder in expanded position; Fig. 5^a is a section of the rudder on the line 5^a—5^a; Fig. 5, on a reduced scale; Fig. 6 is a top plan of the rudder in its expanded position; Fig. 7 shows a modification of the rudder in a position corresponding to that shown in Fig. 3; Fig. 8 is a view similar to Fig. 4 of a modification; Fig. 9 is a view in side elevation of the stern portion of a vessel equipped with one form of my improved apparatus; Fig. 10 shows a modification of the steering and maneuvering transmission.

35

40 Similar numerals refer to similar parts throughout the several views.

Referring to Fig. 9, 1 indicates the stern portion of the hull of the vessel, which may be of any suitable or usual construction, and 45 2 a propeller carried by the shaft 3. The rudder, Figs. 1 to 6, comprises two rectangular side plates 4 and 5 and a substantially U-shaped frame 6. A sleeve or tubular rudder post 7 is fixed to the upper horizontal portion 6^a of the frame 6 and surrounds a part of a shaft or spindle 8. A crank 9 is 50 fixed on the shaft 8 substantially in the height of the upper part 6^a. Connected

with the crank 9 is a rod 10. The rod 10 is hinged to a slide 11, which slides on the frame part 6^a, and to which are connected two links 12 and 13. These links 12 and 13 are pivotally attached to flanged parts 14 and 15 of the plates 4 and 5. To the flanges 14 and 15 are by bolts 16 and 17 also hinged links 18 and 19, which on the other side are connected to a common head, which is slidably mounted on the slide 11. Rods 21 and 22 are hinged to the end of the frame part 6^a by the bolt 23 and to flanges 14 and 15. 60 Preferably the rods 21 and 22 are pivotally mounted on the bolts 16 and 17.

At the lower part 6^b of the rudder there is a similar link system, indicated on the drawings by the same numerals.

70 Triangular shaped plates 24 are preferably hinged to the upper and lower edges of the plates 4 and 5, as indicated at 25. The plates 24 are united in pairs by universal joints 26 consisting of a ball 26^a and a housing in two parts 26^b and 26^c, as shown in Fig. 3^a. To the upper plates 24 may be hinged, as indicated at 27, plates 28, supporting sleeve like parts 29, in which are 75 slidable mounted plates 30 hinged, as indicated at 31, to the lower plates 24. Channels 32 are formed between the plates 4 and 5 on the one side and the plates 28 and 30 on the other side. The plates 28 and 30 are shorter in horizontal direction than the 80 plates 4 and 5, as shown in Fig. 5^a.

85 The slide 11 has eyes 33 and 34. In the eyes 33 is carried a bolt 35 and in the eyes 34 a bolt 36. The slide 11 is supported on the frame 6 by these bolts 35 and 36. The 90 eyes 33 and 34 cooperate with the head 20 for the purpose hereinafter described.

95 Fig. 7 shows a modification in which the plates 24 in lieu of inwardly, as indicated in Figs. 1 to 6, are directed outwardly. In this case the frame 6 must be dimensioned with its horizontal parts 6^a and 6^b aspased from the plate construction, so as to permit the outward movement of the plates 24.

100 The crank 9 and the rod 10 may be substituted by a toothed wheel or pinion 37 and a rack 38, as shown in Fig. 8, the other parts being of the same construction as is illustrated in Figs. 1 to 6.

105 Situated in the vessel is a steering wheel 39, Fig. 9, fixed on a shaft 40, which is jour-

nalled in a rigid part of the vessel. Rigidly attached to the shaft 40 are two sprocket wheels 41 and 42. The sprocket 41 is by means of a chain 43 in driving attachment 5 with a wheel 44 secured to the rudder post 7. The sprocket 42 is by the chain 45, the parts of which cross themselves as at 45^a, connected with a sprocket 46 rigidly secured to a bevel solar wheel 47 in a differential gear 10 47, 48, 49, 50. In conjunction with and supporting the planetary wheels 48 and 50 (that may be one, two or more in numeral) is attached a rim forming a sprocket wheel 51 (see also Fig. 10) having a diameter 15 twice that of the sprocket 46 and by the chain 52 in driving combination with the wheel 53, fixed on the shaft 8. A sprocket wheel 54, fixed to the wheel 49, is by means of a chain 55 connected to a sprocket wheel 20 56, which last mentioned wheel 56 is fixed to a short shaft 57 turnably mounted in the vessel. The sprocket wheel 56 can be rotated by means of a handle 58, which is fixed in position by a pin 59 slidably mounted in 25 the handle and cooperating with a depression in a fixed part 59^a.

The operation of the arrangement is as follows:

Assuming the rudder being collapsed, 30 Figs. 1 and 2, and the wheel 56 being fixed in position. On turning the steering wheel 39 in one direction, the wheels 41 and 42 will be brought in rotation. The wheel 41 thereby, by means of the chain 43, rotates 35 the wheel 44 and the rudder post 7, and the wheel 42 rotates the wheel 46. The latter wheel 46, that is fixed to the solar wheel 47, causes rotation of the planetary wheels 48 and 50, which roll on the solar wheel 49, 40 that is fixed in the vessel by the connection to the temporarily fixed wheel 56. The result is a rotation of the wheel 51 with half the velocity of the wheel 46, but as the wheel 51 is twice in diameter of the wheel 46, the 45 wheel 53 will be rotated with the same velocity as the wheel 44, supposed that the diameters of the wheels 41, 42, 44 and 53 are dimensioned in relation thereto. Thus the rudder post 7 and the shaft 8 will be rotated in unison, bringing the rudder to 50 functionate as a common steering rudder.

If on the contrary the wheel 39 is fixed and the handle 58 is rotated, the transmission 55 56, 55, 54, 49 will bring the wheels 48 and 50 to roll on the now fixed wheel 47, thereby causing the wheels 51 and 53 and the shaft 8 to rotate, whilst the wheel 44, the rudder post 7 and the frame 6 are stagnant. In this case the crank 9, Fig. 2, turns 60 and causes by means of the rod 10 the slide 11 to slide on the frame part 6 forwardly (in the ahead direction of the ship), whereby the plates 4 and 5 are forced to the sides by the links 12 and 13. In an intermediate 65 position, Figs. 3 and 4, the eyes 33 will come

into contact with the head 20 and bring it and the links 18 and 19 to take part of the movement. Thus the plates at an end are brought in the position, shown in Figs. 5 and 6, in which the rear edges of the plates 4, 5 70 and 24 come into contact with each other respectively, forming a pocket in which the water is forced to deflect and return, thereby causing the vessel to reverse. As the plates 28 and 30 are shorter than the plates 4 and 5, an opening 60 is formed between them, through which the water enters the channels 32 and then passes out in a forward direction without meeting the water stream from the propeller. In that manner the 75 forming of eddies is diminished. The movements of the plates 24 relatively to each other is accordingly a double one, partly to a position in which they in pairs are nearly 80 in plane with each other, which movement lasts during the whole expanding procedure, partly to a position in which their rear inclined edges in pairs are brought into contact with each other, which latter movement 85 substantially takes place after the engagement of the eyes 33 with the head 20. This double movement is permitted by the universal joint 26.

If the plates 4 and 5 are not fully closed at the rear edges, a part of the water will 90 pass through the opening thus formed, and the speed of the vessel is thereby regulated and even brought to zero, although the propeller rotates continuously.

In turning the wheel 39, whilst the plates 95 are open, the vessel can be steered simultaneously to the regulation of the speed.

In collapsing the opened rudder the handle 58 is rotated in the opposite direction. The first movement of the crank 9 and the 100 rod 10, Fig. 6, causes the slide 11 to slide rearwardly on the frame 6, whereby the links 12 and 13 open the rear contact between the plates 4 and 5. The eyes 34 next 105 come into contact with the head 20 and the plates are collapsed, the movements being contrary to those above mentioned in the description of the opening of the plates, as 110 is clearly apparent from the drawings.

As the head 20 can slide freely to a certain amount on the slide 11 (or eventually on the frame 6 directly), the plates automatically, in opening or collapsing of rudder, take the positions, in which they made 115 the least resistance to the movements.

Fig. 10 shows a slight modification of the steering transmission mechanism. The steering wheel 39 is rigidly connected to the solar wheel 47 by means of a sleeve 61 and the handle 58 fixed to the solar wheel 49 by means of 120 a sleeve 62. The handle 58 is fixed in position by a lever 63 pivotally mounted on it at 64 and cooperating with a disc 65 fixed to a short shaft 66, which is immovably attached to a stationary part 67 of the vessel. 125

The lever 63 is pressed to frictional contact against the disc 65 by means of a screw 68, and thereby the handle 58 is fixed. The rest of the mechanism is similar to that, 5 shown in Fig. 9.

What I claim is:

1. In a vessel, the combination of a hull, a propeller therefor, a rudder frame, a pair of rudder plates normally flat in engagement with each other, means for pivotally connecting each of the rudder plates with the rudder frame, and means for expanding said rudder plates and bringing the expanded rear edges of the expanded rudder 10 plates into contact with each other.

2. In a vessel, the combination of a hull, a propeller therefor, a vertical rudder frame, a pair of vertical rudder plates normally flat in engagement with each other, 20 means for pivotally connecting each of the rudder plates with the rudder frame, and means for expanding said rudder plates and bringing the expanded rear edges of the expanded rudder plates into contact with each other.

3. In a vessel, the combination of a hull, a propeller therefor, a rudder frame, a pair of rudder plates normally flat in engagement with each other, rods for pivotally connecting each of the rudder plates with the rudder frame, and means for expanding said rudder plates and bringing the expanded rear edges of the expanded rudder 30 plates into contact with each other.

4. In a vessel, the combination of a hull, a propeller therefor, a vertical U-shaped rudder frame the open part of which faces the propeller, a pair of vertical rudder plates, normally flat in engagement with each other, means for pivotally connecting each of the rudder plates with the rudder frame, and means for expanding the rudder 40 plates and bringing the expanded rear edges of the expanded rudder plates into contact with each other.

5. In a vessel, the combination of a hull, a propeller therefor, a rudder frame, a pair of rudder plates normally flat in engagement with each other, means for pivotally connecting each of the rudder plates with the rudder frame, means for expanding the rudder plates, and means for bringing the expanded rear edges of the expanded rudder plates into contact with each other.

6. In a vessel, the combination of a hull, a propeller therefor, a rudder frame, a pair of rudder plates normally flat in engagement with each other, means for expanding the rudder plates, and means for bringing the expanded rear edges of the expanded rudder plates into engagement with each other.

7. In a vessel, the combination of a hull, a propeller therefor, a rudder frame, a pair 60 of rudder plates normally flat in engage-

ment with each other, means for expanding the rudder plates, means for bringing the expanded rear edges of the expanded rudder plates into contact with each other, and a slidable connection between the means for 70 expanding the plates and the means for bringing their rear edges into contact with each other.

8. In a vessel, the combination of a hull, a propeller therefor, a rudder frame, a pair 75 of vertical rudder plates normally flat in engagement with each other, top and bottom plates hinged to the top and bottom of said rudder plates and adapted to normally lie flat in engagement with each other between the rudder plates, and covered by the rudder plates and means for expanding said plates to form a pocket with the rear edges of the rudder plates in engagement with each other.

9. In a vessel the combination of a hull, a propeller therefor, a rudder frame, a pair of vertical rudder plates normally flat in engagement with each other, triangular shaped top and bottom plates hinged at one 90 side to the top and bottom of the rudder plates, a universal joint between the corners of the said top plates, a universal joint between the corners of the bottom plates, means for expanding the plates, and means 95 for bringing the rear edges of the rudder plates and the rear edges of the triangular shaped plates into contact with each other.

10. In a vessel, the combination of a hull, a propeller therefor, a rudder frame, a pair 100 of vertical rudder plates normally flat in engagement with each other, top and bottom plates hinged to the top and bottom of said rudder plates, intermediate plates hinged to the top plates, intermediate plates hinged to 105 the bottom plates said intermediate plates being of a less fore and aft length than the rudder plates and adapted to lie flat in engagement with each other during normal forward operation, a slidable connection between the top intermediate plates and the bottom intermediate plates, and means for expanding the plates to form a pocket with double spaced side walls formed by the rudder plates and the intermediate plates.

11. In a vessel, in combination, a hull, a propeller therefor, a rudder frame, a pair of rudder plates, a rudder post rigidly connected to said frame, a shaft 8, means connected to said shaft for expanding said plates, a differential gear comprising two solar wheels and a plurality of planetary wheels, a rudder wheel connected to one of the solar wheels, a handle connected to the other of the solar wheels, a transmission between said rudder wheel and said rudder post, a rim surrounding and supporting said planetary wheels, and a transmission between said rim and said shaft 8.

12. In a vessel, in combination, a hull, a

propeller therefor, a rudder frame, a pair of rudder plates, a rudder post rigidly connected to said frame, a shaft 8, means connected to said shaft for expanding said plates, a differential gear comprising two solar wheels and a plurality of planetary wheels, a rudder wheel rigidly connected to

one of the solar wheels, a handle rigidly connected to the other solar wheel, a transmission between said rudder wheel and said 10 rudder post, a rim surrounding said planetary wheels, and a transmission between said rim and said shaft 8.

ANDERS JOHAN EMIL RYLANDER.
